United States Patent Office.

JOHN A. HAASE, OF PHILADELPHIA, PENNSYLVANIA.

Letters Patent No. 89,577, dated May 4, 1869.

IMPROVEMENT IN FLOOR-CLAMP.

The Schedule referred to in these Letters Patent and making part of the same.

To all whom it may concern:

Be it known that I, JOHN A. HAASE, of the city and county of Philadelphia, and State of Pennsylvania, have invented a new and useful Improvement in Floor-Clamps; and do hereby declare that the following is a full and exact description thereof, reference being had to the accompanying drawings, and to the letters of reference marked thereon.

The nature of my invention mainly consists of retaining-jaws, which are confined to one of the joists on which the floor is to be laid, and a forcing-screw and clamping-head on a sliding bar, the said screw and shaft working in one of the jaws, and the several parts being constructed and arranged as follows:

In the accompanying drawings, which make a part of this specification—

Figure 1 is an isometrical view of the improved clamp.

Figure 2 is a face view of the retaining-jaw A.

Figure 3 is an edge view of the same.

Figure 4 is a side elevation of the clamping-head D and sliding bar F.

Like letters in all the figures indicate the same parts.

A and A' are retaining-jaws, which are provided with horizontal screws B B, by means of which they are fastened to one of the joists.

The said jaws have their faces checkered with teeth, as seen in figs. 1, 2, and 3, so as to prevent their slipping on the joists.

The jaw A has a horizontal supporting-shoulder a' and a'', which rests on the joist and gives great stability to the said jaw A in preventing its turning during the clamping of the boards.

The part a'' is projected from the contiguous edge of the jaw A, and is strengthened by means of the bracket b.

The jaw A has a slotted elbow, d, which guides the lug e of the jaw A' to preserve the parallelism of the jaws and prevent torsional strain of the screws B B.

C is the forcing-shaft, which turns in a nut in the jaw A, its tail-end bearing against the inner side of the clamping-head D, forcing it against the outer edge of the contiguous board, to be clamped, as said shaft is screwed forward by means of the handle E, the shaft F of the head sliding in the hole e, through the jaw A.

When desired, the forcing-shaft C may have a smooth periphery, and be operated by means of a cam or lever.

It will readily appear that the retaining-jaws being teethed to prevent slipping on the joist, and the standing jaws A having a support which rests upon the top of the joist, that great stability is given to said jaws; and that as the clamping-head being permanent to its shaft, which has a bearing-surface through the whole width of the jaw A, that it must be moved without the tendency to spring from its normal position, as in other floor-clamps.

What I claim as new, and desire to secure by Letters Patent, is—

1. The construction of the jaw A with a supporting-shoulder, a' a'', substantially in the manner described, and for the purpose set forth.

2. The construction of the jaws A and A' with the slotted elbow d and lug e, substantially as described and for the purpose specified.

3. A floor-clamp, composed of the retaining-jaws A and A', retaining-screws B B, clamping-head D, guiding and supporting-shaft F, and forcing-shaft C, when the several parts are constructed and arranged for joint operation, substantially in the manner and for the purpose set forth.

In testimony that the above is my invention, I have hereunto set my hand and affixed my seal, this 25th day of February, 1869.

JOHN A. HAASE. [L. s.]
